tion of Delaware

Application October 4, 1938, Serial No. 233,164

4 Claims. (Cl. 250—20)

Our present invention relates to automatic gain control systems of the type using substantially linear power detectors, and more particularly it relates to receiving systems employing signal detectors utilizing degenerative feedback for linear operation.

One of the main objects of our present invention is generally to improve the operation of detectors of the plate rectification type; the improvement involving the feeding back to the detector input of signal energy in degenerative phase, and the simultaneous use of the direct current voltage component of the detected signal energy for automatic volume control (AVC) action.

Another important object of the invention is to provide in a receiving system a detector having a normally non-linear detection characteristic, and detected signal energy being fed back in degenerative phase to at least one network prior to the detector thereby to render said characteristic substantially linear; the direct current voltage component of the detected energy being utilized to maintain the carrier amplitude at the detector input circuit substantially uniform.

Another object of our invention is to improve radio receivers of the type normally provided with a non-linear detector, detected energy being fed back to a preceding amplifier in degenerative phase thereby to improve the linearity of the detector, and the direct current voltage component of the detected energy being utilized to vary the amplifier gain in a sense such as to maintain the carrier amplitude at the detector input substantially uniform.

Another object of our invention is to provide a detector of the biased type wherein audio degenerative feed-back is employed between the output and input circuits, and the detector characteristic is thereby linearized; the direct current voltage component in the detector output circuit being employed for varying automatically the gain of at least one amplifier preceding the detector.

Still other objects of our invention are generally to improve detection systems, and more especially to provide detection systems utilizing degeneration and which systems are not only reliable and efficient in operation, but are economically manufactured and assembled in radio receivers.

The novel features which we believe to be characteristic of our invention are set forth in particularity in the appended claims; the invention itself, however, as to both its organization and method of operation will best be understood by

reference to the following description taken in connection with the drawing in which we have indicated diagrammatically several circuit organizations whereby our invention may be carried into effect.

5 In the drawing:

Fig. 1 schematically shows a circuit diagram embodying one form of the invention.

Fig. 2 illustrates a modified form of the invention.

10 Referring now to the accompanying drawing, wherein like reference characters in the different figures indicate similar circuit elements, there is shown in Fig. 1 those networks of a radio receiver which are essential to a proper understanding of the present invention. It will be understood by those skilled in the art that the networks feeding the amplifier tube 1 may be those commonly employed in any desired type of receiving system, such as a superheterodyne receiver. Let it be assumed that tube 1 is embodied in the intermediate frequency (I. F.) amplifier network of the receiver. Hence, the input electrodes of tube 1 are coupled to the tuned input circuit 2, and the latter is fixedly resonated to the operating I. F. Of course, the networks preceding the input circuit 2 will comprise the usual signal collector followed by a converter stage which feeds one or more I. F. amplifiers.

15 The plate circuit of amplifier 1 includes the output circuit 3 which is fixedly tuned to the I. F. value, and circuit 3 is reactively coupled to input circuit 4 of the detector tube 5; it being understood that circuit 4 is also tuned to the I. F. 20 The detector tube 5 is of the biased type; that is to say, it functions as a plate rectification type of detector. The cathode 6 of tube 5 is connected to an intermediate point on the voltage supply bleeder resistor 7.

25 The grounded side of resistor 7 is the positive terminal of the potential source; plate 8 is connected to said terminal through a path which includes load resistor 9 and the choke coil 10. The input grid 11 of tube 5 is connected to the negative terminal of resistor 7 through a path including the coil of the input circuit 4; a condenser 12 of low impedance to carrier and audio frequency currents being connected in shunt across that portion 7' of resistor 7 which is connected between the cathode and the grid of tube 5. The condenser 13 connects the cathode tap on resistor 7 to ground for I. F. currents.

30 The audio voltage developed across resistor 9 is transmitted through the condenser-resistance coupling 14 to the following audio amplifier and

it will be understood that one or more amplifiers may follow the latter; the amplified audio energy will then be reproduced in any desired type of reproducer. The condenser 15, shunted across load resistor 9, bypasses carrier frequency currents around the resistor. The normal, or maximum amplification, bias for the input grid of amplifier 1 is secured by maintaining the cathode of tube 1 at ground potential, and connecting the low potential end of input circuit 2 to the negative end of load resistor 9. A degenerative path is provided which comprises a lead 16 which has in circuit therewith a variable resistor 17. The grid end of adjustable resistor 17 is connected to ground through a network which includes variable resistor 18, coil 19 and condenser 20 in series, the variable condenser 21 being connected in shunt with the last named three series elements.

The potential across the grid bias resistor section 7' is such as to bias the grid 11 for normal plate rectification by tube 5. As is well known, the detection characteristic of such a biased detector has considerable curvature in the weak signal input region, and approximating linearity for strong signal inputs. The non-linearity of the characteristic introduces distortion into the audio output. By feeding back signal voltage, developed across coil 18 in degenerative phase, the distortion introduced at the detector is cancelled out. It will be observed that the variable resistor 17 functions to control volume; it can act as the manual volume control device of the receiver. The normal voltage (D. C.) across resistor 9 maintains the grid of tube 1 at a normal negative bias with respect to its grounded cathode. As the carrier amplitude at the signal collector increases, the D. C. voltage across resistor 9 increases with the result that the gain of amplifier 1 is decreased. Prior tubes may be gain-controlled, in addition to tube 1, by tapping off the D. C. voltage component from lead 16 and transmitting the voltage to the controlled tubes through an audio filter 22. Either of the elements 18 or 21 may be used as a tone control element. Thus, increasing 21 will increase the high audio frequency components; increasing resistor 18 will decrease low audio frequencies. The condenser 20 grounds the grid of tube 1 for I. F. currents, but blocks direct current.

In Fig. 2 is shown a modification wherein the biased detector tube 5 feeds audio voltage, developed across load resistor 9, in degenerative phase to the detector input circuit 4. Feedback is accomplished by connecting the path including variable resistor 30 and condenser 31 between the plate end of resistor 9 and the low potential end of the detector input coil. The AVC bias is transmitted over the lead 32 to the grids of the controlled signal transmission tubes. The AVC path includes an appropriate audio filter network 33. Proper energizing potentials for the amplifier and detector tubes is provided by the common voltage supply potentiometer 40. The plate 8 is connected to a desired positive voltage point 41; the cathode 6 of the detector tube is connected to a relatively negative point 42. The cathode 1' of amplifier 1 is connected to point 43 which is negative with respect to point 41. The normal negative bias (maximum gain) of amplifier 1 is secured by having the normal voltage across resistor 9 exceed the potential difference between points 41 and 43 by the value of the desired no-signal negative bias.

Grid 11 of the detector tube 5 is maintained

at the normal negative bias between ground and point 42; the grid being connected to ground by resistor 50 which is shunted by the bypass condenser 51. Network 50-51 has a low I. F. impedance but high audio impedance. It is across this impedance that the fed back audio current through 30-31 builds up voltage to apply in inverse phase to grid 11. Resistor 30 acts as a manual volume control device; it adjusts the degree of negative feedback through path 30-31. The degenerative, or negative, audio feedback in the detector stage acts to reduce the harmonic distortion due to the non-linearity of the detection characteristic. Since the tube 15 functions as a biased detector, amplification of the audio voltage is secured despite the reduction in audio intensity due to negative feedback. The characteristic of the detector is made to approach linearity.

Fig. 1 differs from Fig. 2 in that feedback in Fig. 1 is of the I. F. components including the audio sidebands. The output of a detector contains not only audio frequency components, but also the radio frequency components (I. F. and sidebands) present in its input circuit. Ordinarily these radio frequency components are bypassed, and the audio frequency components only are utilized. In Fig. 1 the coil 10 in the plate circuit has I. F. and sideband voltage built up across it; this voltage is fed back through lead 16 and feedback control impedance 17 to the circuit 21-18-19-20 which is likewise an I. F. impedance, although usually of lower magnitude of I. F. impedance than circuit 2. The I. F. component fed back is so phased that the original modulation components are opposed. As is well known, distortion in a square law detector is proportional to the square of the modulation; feeding back energy to oppose the original modulation of the I. F. wave decreases distortion not only by feedback action as in Fig. 2, but, also, by reduction of effective input modulation.

While we have indicated and described several systems for carrying our invention into effect, it will be apparent to one skilled in the art that our invention is by no means limited to the particular organizations shown and described, but that many modifications may be made without departing from the scope of our invention, as set forth in the appended claims.

What we claim is:

1. In a detection network, a tube having at least a cathode, a plate and a control grid, a signal input circuit connected between the grid and cathode, a resistive impedance connected between said plate and cathode, a path of low impedance to audio frequency currents connected between a point on said resistive impedance and said control grid, said path being constructed to impress audio voltage developed across said impedance upon said grid in degenerative phase with the audio modulation on the carrier at said input circuit, a second connection to said impedance for deriving therefrom solely a direct current voltage developed thereacross by the tube space current, and means for biasing the grid so that the network detects by plate rectification.

2. In a detection network, a tube having at least a cathode, a plate and a control grid, a signal input circuit connected between the grid and cathode, a resistive impedance connected between said plate and cathode, a path of low impedance to audio frequency currents connected between a point on said resistive impedance and

said control grid, said path being constructed to impress audio voltage developed across said impedance upon said grid in degenerative phase with the audio modulation on the carrier at said input circuit, and means for biasing the grid so that the network detects by plate rectification, an amplifier tube preceding said detector tube, and direct current voltage connections between the amplifier input electrodes and said impedance whereby the detector space current flow through said resistive impedance provides bias for said amplifier tube.

3. In a detection network, a tube having at least a cathode, a plate and a control grid, a signal input circuit connected between the grid and cathode, a resistive impedance connected between said plate and cathode, a path of low impedance to audio frequency currents connected between a point on said resistive impedance and said control grid, said path being constructed to impress audio voltage developed across said im-

pedance upon said grid in degenerative phase with the audio modulation on the carrier at said input circuit, and means for biasing the grid so that the network detects by plate rectification, said path including an adjustable resistor to vary the feedback therethrough over a wide range of values whereby the adjustable resistor acts as a manual volume control device.

4. In combination with a biased detector tube having a signal input circuit and an audio output circuit, means, including a series path of capacity and variable resistance, for degeneratively feeding audio energy from the output circuit to said input circuit, a signal amplifier feeding signals to said input circuit, and means, responsive to the variation in intensity of the direct current voltage in said output circuit, for varying the amplifier gain.
